LOCK

Edwin W. North, Rockford, Ill., assignor to
National Lock Co., Rockford, Ill., a corporation
of Delaware

Application January 23, 1933, Serial No. 653,632

27 Claims. (CL 70—113)

This invention relates to locks and more particularly to permutation locks of the shackle type. Objects of the invention are: to provide in a shackle lock an improved locking mechanism of a type having a snap-latching action and permutation controlled to effect release of the shackle-retaining means; to provide such a locking mechanism which in the released condition will maintain such a relation of parts as to prevent accidental locking action of the mechanism while the shackle is withdrawn from the lock housing, thus obviating any necessity to work the lock combination in order to permit locking the shackle; to provide a mechanism of the character stated which will automatically lock when the shackle is inserted in position to be locked, thus avoiding the possibility of accidentally leaving the mechanism in releasable condition; to provide in conjunction with such mechanism key-controlled means for establishing a release condition, whereby locks embodying the invention and used as school locker locks may be under the control of the school authorities through the aid of a master key for releasing the locks in order to obtain inspection of lockers; to provide structural improvements certain of which are of special applicability to permutation or to combined key and permutation locks and others of more general applicability; and in general to provide an improved permutation pad lock, and a combined key-controlled and permutation-controlled pad lock, of a highly practical, serviceable and reliable character, well adapted for the purposes of a school locker lock.

One practicable construction of combined permutation and key-controlled pad lock embodying the invention is shown in the accompanying drawings, in which:

Fig. 1 is a front elevation of said pad lock.
Fig. 2 is a view looking into the rear housing member and showing in front elevation a part of the locking mechanism including a locking dog for engaging the shackle and a key-operable carrier for said dog, the parts being shown in shackle releasing position.

Fig. 3 is a sectional view taken longitudinally of the axis of the key barrel.

Fig. 4 is a view similar to Fig. 2 with the shackle in locked position.

Figs. 5 and 6 are detail views of certain spacer plates.

Fig. 7 is a detail view of the dial operating knob.

Fig. 8 is a key for releasing the lock.
Fig. 9 is a view looking into the lock housing

and showing a part of the disk tumbler mechanism by which the shackle-engaging dog is normally locked in shackle-engaging position, this view showing the normal locked relation of the parts.

5

Fig. 10 is a view similar to Fig. 9 showing the parts in relation to release the shackle-engaging dog.

Fig. 11 is a similar view showing the shackle withdrawn from its locked position in the lock 10 housing and the shackle-engaging dog displaced to its released position.

Fig. 12 is an abutment ring associated with the tumbler disk shown in Fig. 14.

Fig. 13 is the disk tumbler which is directly 15 operable by the dialing means.

Fig. 14 is one of the other disk tumblers.

Fig. 15 is a key tumbler.

Fig. 16 is a perspective view of the shackle-engaging locking dog and its key-operable carrier. 20

Fig. 17 is a front plate having a sleeve on which the loose disk tumblers are mounted and in which the key barrel is journaled.

Fig. 18 is the front housing member.

Fig. 19 is a flanged plate fitted and secured in 25 the rear housing member.

Fig. 20 is a detail fragmentary view showing the position of the loose disk tumblers at the instant when in the shackle-locking operation the locking dog passes from engagement with said 30 disk tumblers.

Referring to the drawings, the specific construction embodied in the illustrative lock is described as follows:

The lock shackle 1 is represented as a sliding 35 U-shaped shackle, having a long arm permanently retained in the lock housing and a short arm releasably retained therein.

The shackle 1 has a notch 2 engaged by a pivoted locking dog 3. This locking dog, which 40 is pivoted on the stud 4, is normally locked in shackle-engaging position by a set of disk tumblers which can be adjusted to release the dog. Upon establishing release conditions the dog can be displaced from the shackle notch by 45

pulling out the shackle to the released position shown in Fig. 11. As the shackle is returned to the locked position it encounters and actuates a lever arm 8 extending from the locking dog, thereby rocking the dog into engagement with the shackle notch. A double acting spring 6 resists initial movement of the locking dog in either direction but actuates the dog to snap into the position toward which it is started. This spring 50 as shown in Figs. 2, 4 and 16 may comprise a 55

stressed resilient device acting between the locking dog and an abutment provided by the lug 7, said spring device having its ends pivotally seated in V-shaped notches in the dog and abutment, 5 and the arrangement being such that the reaction of the spring is exerted against the dog at one side of its pivot 4 when the dog is in shackle-retaining position and at the other side of said pivot when the dog is thrown out of the shackle notch; or in other words the spring must be forced under stress past a dead center position relative to the dog pivot 4 in moving the locking dog from one position to the other. The movement of the dog in the shackle-engaging direction is limited by abutment of the lever arm 5 against the lug 7, and the movement of the dog in the opposite direction is limited by the stud 8.

From the foregoing it will be seen that the double acting spring 6 causes a snap action of the locking dog in moving to or from shackle-engaging position, and yieldingly holds the dog in the position to which it is thrown; so that the releasing of the shackle requires pulling it outward against an initial spring resistance, while 25 the replacement of the shackle requires pushing it inward against a like resistance, with an accompanying desirable snap-latching action as soon as the resistance is overcome.

By arranging the locking dog behind the disk tumblers and providing the dog with a lateral lug 9 overlying the peripheries of the disk tumblers, which coact with said lug to lock the dog in shackle-engaging position, an advantageous compactness is obtained, permitting the 30 lock to be manufactured in the comparatively small sizes desired for school locker locks.

The disk tumblers 10, 11, 12, otherwise referred to as permutation disks, are elements of a well known type of permutation mechanism including 40 a dialing means the rotary member of which is operatively connected with one of the disks; the other disks being independently rotatably mounted and each of the disks having a shoulder or projection in the path of rotation of a shoulder or projection on the adjacent disk, so that by a predetermined manipulation of the rotary dialing member, for working the "combination" for which the lock is set, the disks are brought to a relationship to release the dog. Such release is effected by registration of peripheral recesses in the several disks with each other in the position shown in Fig. 10, so as to allow entry of the lug 9 into the said recesses of the disks and consequent release movement of the locking dog as shown in Fig. 11.

Dialing means is provided as shown in Figs. 1 and 3 by a rotary dial plate 13 mounted on the front of the lock housing, operable by the knob 15, and a fixed pointer 14 shown in Fig. 1 as a 50 notch in the front face of the lock housing. The dial knob 15, which is rotatably mounted on a fixed sleeve 16, has a reduced extension which passes through the front wall of the lock housing and carries the permutation disk 10, which is fast 55 on the inner end of said extension. The other two disks 11 and 12 are rotatably mounted on said sleeve 16, with interposed non-rotatable spacing washers 17 keyed on said sleeve.

The disk 10 which is attached to and directly operated by the dial knob, is separately shown in Fig. 13. Its recess to receive the dog lug 9 is indicated at 10a. This disk, which is very slightly or almost imperceptibly larger than the others, also has a series of false recesses 10b to coact with 70 the dog lug so as to foil any attempt on the part

of unauthorized persons to learn the lock combination. The projection on the disk 12 for picking up the next disk is indicated in dotted lines at 10c.

Fig. 14 shows the next disk 11, having a recess 11a to receive the dog lug 9 and a peripheral notch 11b for a function presently to be described. This is a thin flat disk having an annular series of holes, and is associated with the adjustable abutment ring 11c shown in Fig. 12. This abutment ring 11c has an arm providing an abutment 11d and a bent terminal finger 11e to enter and project through one of the holes in the disk 11. Said disk 11 and the abutment 11c with which it is equipped may be considered as a unit, the abutment ring providing at one side the abutment 11d in the path of the projection 10c of the first disk and at the other side the projection 11e to pick up the third disk 12, which is similar to 11 and equipped with a similar abutment ring 12c as 20 shown in Fig. 3.

The described construction of the permutation disks is exemplary of one appropriate construction of disks adapted for manufacture as sheet metal stampings and suitable for compact assemblage in a small lock construction and of such character as to permit different working combinations for different locks of the same construction, the combination depending upon the angular relation of the abutment rings 11c and 12c and the peripheral recesses in the disks 11 and 12. The manufacturer may put out as many different locks of identical construction, each operable with a different lock combination, as the number of changes which can be made in the relationship of the disk 11 and its abutment ring 11c, multiplied by the number of changes which can be made in the relationship of the disk 12 and its abutment ring 12c; and the number of permissible combinations may be further multiplied by the use 30 in different locks of first disks 10 having their lugs 10c at different angular relations to the recess 10a.

It will be understood that by rotating the dial knob in opposite directions, as required to work the particular combination for the particular lock, 45 the several disks will be adjusted with their peripheral recesses in registration in the position shown in Fig. 10; the third disk having first been set by rotating the dial as required to cause the first disk to pick up the second and the second to pick up the third and bring it to said position shown in Fig. 10, corresponding to registration of a specific dial division with the pointer; the second disk having next been set by a reverse rotation of the dial to cause the first disk to again pick up the second and bring it to the same position, corresponding to registration of another dial division with the pointer; and the first disk having last been set by a rotation of the dial in the first direction to bring it to the same position corresponding to registration of a third dial division with the pointer.

Having thus worked the lock combination to bring the disks to the position shown in Fig. 10, the sliding shackle may be pulled out to withdraw 65 its short arm from the lock housing, the locking dog being forced to the released position shown in Fig. 11 first by the up-pull of the shackle against the nose of the dog and then by the action of the double acting spring 6. Since the spring holds 70 the locking dog in the position shown in Fig. 11, with the lug 9 in the peripheral recesses of the three disks, it is obvious that there can be no derangement of the lock mechanism while the shackle is in released position such as to necessi- 75

tate a reworking of the combination to permit relocking the shackle. To relock it is only necessary to push the short arm of the shackle into the lock case, with the accompanying snap latching of the locking dog as already explained.

By means now to be described, the replacement and snap latching of the shackle is accompanied by an automatic breaking of the lock combination, so as to obviate the necessity of working the dial to disestablish release conditions, consequently insuring that the student or other person using the lock will not accidentally leave it in the releaseable condition.

As shown in Fig. 9, the disk 11 is normally held in a position to prevent entry of the lug 9 of the locking dog into the disk recess 11a, thus locking the dog in shackle-engaging position regardless of the position of the other disks 10 and 12. The disk 11 is so held by a spring pressed pawl 18 having a cam-shaped part 19 engaging the correspondingly shaped notch or depression 11b in the edge of the disk. This pawl is shown as a pivoted lever arm actuated by the spring 20. The notch 11b is so situated relative to the recess 11a that when the disk 11 is in position to permit entry of the locking dog lug 9 into said recess 11a the point of the pawl cam-part 19 bears on the edge of the disk just above the notch 11b, as shown in Fig. 10. When the dialing mechanism is manipulated to work the required lock combination, all of the three disk tumblers 10, 11, 12 are brought to the same position as the disk 11 in Fig. 10, with their peripheral recesses in registration in position to allow entry of the lug 9 into said recesses, thus releasing the locking dog. When the shackle is pulled out the locking dog snaps to the release position shown in Fig. 11. In this movement the toe of the lug 9 coacting with the lower left hand corner parts of the lug-receiving recesses of the three disks 10, 11, 12 moves the disks counterclockwise from the position shown in Fig. 10 to the position shown in Fig. 11. The position of the disks in Fig. 11 is one dial notch removed from the position in Fig. 10. In the Fig. 11 position the notch 11b of disk 11 is engaged by the cam part 19 of the point 18, the position of the disk 11 in Fig. 11 being the same as in Fig. 9. Now when the shackle is returned to the position shown in Fig. 10, and as the locking dog snaps back to shackle-engaging position, the lug 9 coacting with the upper parts of the right hand walls of the lug-receiving recesses of the three disks moves them in a clockwise direction or toward the position shown in Fig. 10. In this action the disk 11 is rotated against the resistance of the pawl 18 to almost but not quite the position shown in Fig. 10, so that in this movement the cam part 19 of the pawl rides almost but not quite out of the notch 11b. The result is that at the instant the lug 9 of the locking dog moves out from the lug receiving recess of the disk 11, the cam part 19 of the pawl 18 is bearing against the upper inclined surface of the notch 11b as shown in Fig. 20, and by coaction of said part 19 with said inclined surface the disk 11 is immediately turned counterclockwise to the position shown in Fig. 9. In the Fig. 9 position the recess 11a of disk 11 is out of register with the corresponding recess of disk 10, and out of position to allow entry of the locking dog lug 9 into said recess 11a, or in other words the position of the disk 11 in Fig. 9 is such as to lock the locking dog, as already explained.

Preferably the third disk tumbler 12, which does not appear in Figs. 9, 10 and 11 because it

is concealed in these views by the disk 11, is precisely like the disk 11, said disk 12 having a notch which corresponds to the notch 11b and which is likewise normally engaged by and otherwise coacts with the cam part 19 of the spring pressed holding pawl 18 in the same manner as explained with reference to the disk 11, so that the two disks 11 and 12 are utilized in cooperation with the pawl in accomplishing the function which has just been described.

Thus the return of the shackle to position for locking it automatically effects its locking, by reason of the automatic latching action of the locking dog 3 and the automatic setting of the disk tumblers 10 and 12, or at least one of them, in a position to lock the locking dog, and out of register with the disk 10, consequently requiring a subsequent re-dialing manipulation or re-working of the required combination in order to effect any subsequent release of the locking dog.

It being desirable that permutation padlocks used as school locker locks should be under the control of the school authorities by the aid of a master key, the present invention provides, in conjunction with the permutation-controlled snap-locking mechanism above described, a novel key-operable mechanism the function of which is to release the locking dog from its locked coordination with the disk tumblers, so as to permit the shackle to be released and withdrawn and to be replaced and locked independently of permutation control. For this purpose, the pivoted locking dog 3 together with its motion-limiting stops and spring 6 is carried by a carrier plate 21, best shown in Fig. 16, which is normally locked in the fixed position shown in Fig. 4 but is key-releasable and operable to and from the unlocking position shown in Fig. 2. In moving to and from the unlocking position, the carrier plate swings on the fixed pivot stud 22, its movement in the unlocking direction being limited by the stop 23, while its movement in the opposite direction is limited by the lock housing. In this movement the pivoted spring-held locking dog 3 swings with the carrier plate on the carrier pivot 22 which is located near the nose of the dog. Thus as the carrier plate moves to the unlocking position the dog 3 rocks on the pivot 22 in a direction to cant the shackle-engaging nose of the dog downwardly and to move the lug 9 away from the peripheries of the disk tumblers. The dog 3 being thus released from the locking action of the disk tumblers, the shackle is accordingly releasable and may be pulled out with accompanying displacement of the locking dog, as shown in Fig. 2.

The key-unlocking operation is performed with a proper key 24 shown in Fig. 8. The key operates in a longitudinally slotted rotatable key post 25, shown having an enlarged head 26 fitted in the stationary key-barrel or sleeve 16. A bearing 60 for the rear end of the key post is provided at 27. To insert the key it is necessary to register the longitudinal key-slot in the post with a notch in the flanged fore end of the key barrel, which notch is shown at 28 in Fig. 1. The key post passes 65 through an opening 29 in the locking dog carrier plate 21 which is engageable by the bit of the key in the slotted part 30 of said carrier plate for actuating the plate. Associated with the carrier plate are key tumblers 31 coacting with a stump 70 or fence 32 on the carrier plate to lock said plate in its normal position shown in Fig. 4, in which position said carrier plate functions as a fixed frame member in the lock housing. The key tumblers are pivoted on to stud 29 and have 75

notched ends engaging the stump 32 and are held in such engagement by the springs 34.

The proper key when inserted full way in the key post and turned in a clockwise direction will 5 displace the key tumblers to a position to permit entry of the stump 32 into the tumbler slots 35, thus releasing the locking dog carrier plate 21, and by the continued turning of the key its bit 10 engaging in the slotted part 30 of the carrier plate 10 will actuate it to the unlocking position shown in Fig. 2. As already explained this releases the locking dog 3 from the locking action of the disk tumblers by the shifting of the dog into a position 15 with its lug 9 away from the disk tumblers, whereupon the shackle may be pulled outward to released position, shown in Fig. 2.

To relock the shackle after the key-unlocking 20 operation, the shackle is pressed back against the lever arm 5 of the locking dog, with accompanying reverse turning of the key to restore the dog carrier plate 21 to its normal locked position, thus restoring the locking dog to its normal shackle-locking position under permutation control.

25 Summarizing briefly, the shackle can be released and pulled out upon performing the required dialing operation to work the lock combination, thereby adjusting the disk tumblers in position to release the locking dog. In pulling 30 out the shackle it displaces the dog which under the action of its spring snaps free of the shackle. While the shackle is released the spring-held dog is maintained in fixed relation with the dial knob and disk tumblers, preventing such a misadjustment as to necessitate redialing for relocking. 35 To relock the shackle it is only necessary to force it back into position for locking it, in which movement its actuation of the lever arm 5 of the locking dog initiates a return movement of the dog which then under the impulse of 40 its spring snaps into shackle-engaging position. This operation is accompanied by an automatic setting of the tumbler disks to break the lock combination and establish a locked condition such as to necessitate redialing for subsequent un-locking. But by means of the key, the normally 45 fixed carrier plate 21 can be released and actuated to change the position of the locking dog relative to the disk tumblers sufficiently to allow 50 releasing action of the dog and consequently to permit the withdrawal of the shackle with such accompanying releasing action. And by forcing back the shackle with an accompanying reverse turn of the key, the parts are restored to the 55 normal locked condition, whereupon the key may be withdrawn and the lock left for use as a permutation lock.

Certain constructional features of the illustrative lock will now be described.

60 The lock housing comprises two sheet metal parts, namely the cup-shaped rear housing member 36 and flanged front plate 37 which is fitted in said rear housing member and permanently retained by spinning the housing rim over the front 65 plate as indicated at 38 in Fig. 3. The front plate is formed to provide an annular shoulder 39 surrounding the rotary dial plate 43. In the rear housing member a flanged liner plate 40 is fitted and fastened by the rivet 41. This liner plate, 70 formed with the bearing on the key post and with the pivot pin 23 for the key-tumblers, is virtually a part of the lock housing but is made as a separate part for manufacturing convenience. It has the further advantage of reinforcing and 75 stiffening the sheet metal lock housing. A parti-

tion plate 42 carrying the key-barrel or sleeve 16 is fitted in the lock housing between the flanged liner plate 40 and flanged front plate 37. The locking dog carrier plate 21 and locking dog 3 and the key-tumblers 31 are arranged in the rear housing member between the plates 40 and 42, with suitable spacer plate elements 43 and 44 between said parts and the partition plate 42 as shown in Fig. 3. These spacer elements, shown in Figs. 5 and 6, are arranged as shown in Figs. 2 10 and 4, the element 43 being mounted on the tumbler pivot stud 23 and the element 44 being mounted on locking dog pivot stud 4 and a projecting teat on the stump 32, so that the spacer element 44 swings with the locking dog carrier. 15 The construction described facilitates assemblage. The locking dog, its carrier plate and key-tumblers having first been mounted in the rear housing member, the spacer elements 43 and 44 are applied and the key-post is put in. Then the 20 partition plate having the key-barrel or sleeve 16, assembled with the disk tumblers 11 and 12, is put into place, slipping the key-barrel over the key post. Then the flanged front plate 37 having the dial plate, dial knob and first permutation 25 disk 10 assembled therewith as a unit as clearly shown in Fig. 3, is fitted in the rear housing member against the partition plate 42 and secured by spinning the outer housing rim at 38, thus securing all the parts of the lock in assembly. 30

The liner plate 40 and partition plate 42 are formed with cooperating recessed flanges 45, 46 to provide a guide for the reduced swiveled end 67 of the long shank of the shackle, the said reduced part of the shackle shank being formed with shoulders at each end to limit the sliding movement of the shackle in and out, as is apparent. The housing is provided with the usual openings for the shackle, and as shown in Figs. 40 17 to 19 the parts 40, 42 and 37 are formed with suitable cut-away portions to accommodate movable parts of the lock mechanism. 45

As shown in Fig. 3, the dial plate 43 is frusto-conical, providing an enclosed space between it 45 and the front plate of the lock housing. In this space is a clicker ring 48 affixed to the dial knob extension 45 and having a rib which rides on the annular toothed surface 49 on the front housing plate, producing a click every time the dial is turned one notch. The clicker ring is yieldingly 50 pressed against the front housing plate by an undulating or wavy sheet metal ring 48a. The dial plate 43, clicker ring 48 and first permutation disk 10 are all fitted to the dial knob extension 55 45a and keyed therewith by means of internal lugs on said parts engaging the longitudinal slots in said knob extension. This dial knob extension is of stepped diameter, providing seats on which the dial and clicker ring, front housing plate and first permutation disk are respectively fitted, and the inner end of said extension is swaged to the disk 10, whereby the parts mentioned are secured in assembly. 60

It will be understood that the specific construction embodied in the illustrative lock is exemplary, that changes in details of construction and arrangement are permissible, and that parts of the invention may be variously used without the whole, so that the foregoing description is not 65 to be taken as limiting the invention otherwise than as defined by its claims.

The member hereinbefore designated as the locking dog may otherwise be termed a lock bolt, it being the movable member which directly en- 70 75

gages the shackle and by which the shackle is locked by the mechanism controlling said member.

What I claim as my invention, and desire to secure by Letters Patent, is:

1. In a shackle lock, a shackle-locking mechanism including a pivoted locking dog engageable with the shackle, disk tumblers for locking said dog in shackle-locking position and adapted to be manipulated to release the dog, said dog when released being displaceable by withdrawal of the shackle, double-acting spring means arranged to hold the dog either in shackle-engaging position or retracted position, said spring means adapted when the dog is moved from either position a sufficient distance to overcome its resistance to actuate the dog to snap into the other position, and means operable by insertion of the shackle to cause the operation of the dog to engage the shackle. 10
2. In a shackle lock, a shackle-locking mechanism including a pivoted locking dog adapted to engage the shackle when inserted, disk tumblers for locking said dog in shackle-engaging position and adapted to be manipulated to release the dog, said dog when released being displaceable by withdrawal of the shackle, the tumblers having means engaged by the dog whereby movement of the dog to and from released position causes a rotation of the tumblers, spring pressed means having cam means bearing against certain of said tumblers, the latter having cam surfaces which when the dog moves to shackle-engaging position are brought to a position such that said cam means bears thereon and shifts the tumblers having such cam surfaces to a position to cause the locking of the dog. 20
3. A permutation lock having a movable lock bolt and permutation disks cooperable therewith to lock said member in a protracted position, said disks having recesses adapted when brought into registration with a part of said lock bolt to admit said part accompanying a retracting movement of said lock bolt, said lock bolt in moving to and from retracted position adapted to turn the set of disks by coaction of said part with walls of said recesses, at least one of said disks being normally held in position to prevent retracting movement of said lock bolt, and a spring pressed pawl having a cam-shaped part engaging a correspondingly shaped notch in said disk whereby it is normally so held; the arrangement being such that in the adjustment of said disks to release said lock bolt the pawl rides out of said notch, and in the movement of said lock bolt to its retracted position the said notched disk is turned to its normal position, and in the protracting movement of said lock bolt said notched disk is so displaced from its normal position that the pawl rides up a wall of the notch but not clear out of the notch, with the result that when said disk is freed from engagement with said lock bolt the pawl will exert a camming action causing a return of said disk to its normal position. 30
4. A lock having a lock bolt, disk tumblers normally locking the same and manipulatable to release the same, said tumblers and lock bolt having coactive parts whereby said tumblers are rotated by said lock bolt as it moves to and from retracted position, certain of said tumblers having cam surfaces, and spring-pressed camming means cooperable with said surfaces, said cam surfaces being so located in relation to the tumbler parts with which said lock bolt coacts as to cause rotation of the tumblers, that the rotation of the tum- 40
- blers accompanying retraction of said lock bolt brings said surfaces into a normal position engaged by said spring-pressed camming means, while the reverse rotation accompanying movement of said lock bolt from retracted position shifts said surfaces from normal position but not out of engagement with said camming means, whereupon the coaction of said camming means with said surfaces causes a rotation of the tumblers having such surfaces to normal position for locking said lock bolt. 50
5. In a shackle lock, a shackle-locking mechanism including a pivoted locking dog engageable with the shackle, a means to cause a snap action of the dog to engage the shackle when the shackle is inserted, disk tumblers cooperable with the dog to lock the same in shackle-engaging position, means to cause such cooperation of the tumblers with the dog, means manipulatable by a predetermined combination of manual operations to adjust said tumblers to establish a release condition of the mechanism, and key-operable means carrying said dog by which the dog can be moved relative to the tumblers in a manner establishing a release condition. 60
6. In a shackle lock, a shackle-locking mechanism including a pivoted locking dog engageable with the shackle, disk tumblers for locking said dog in shackle-engaging position and adapted to be manipulated to release the dog, key-controlled means carrying said dog and operable to shift the pivot of the dog in a direction to tilt the dog to a position in which it is released from the locking action of the tumblers, said dog when released in either manner being displaceable by withdrawal of the shackle, the dog being re-engageable with the shackle upon reinsertion of the shackle. 70
7. In a shackle lock, a shackle-locking mechanism including a pivoted locking dog engageable with the shackle, disk tumblers for locking said dog in shackle-engaging position and adapted to be manipulated to release the dog, means operable by insertion of the shackle to cause the operation of the dog to engage the shackle, a key-operable means to which the dog is pivoted operable to tilt the dog in a manner to release it from the locking action of said tumblers by shifting the pivot of the dog, and key-tumblers normally locking said key-operable means. 80
8. A combined key and permutation lock having a key-operable pivoted carrier, key-controlled tumblers by which the carrier is normally locked in one position, a lock bolt pivoted to said carrier, disk tumblers cooperable with said lock bolt to lock the same when said carrier is in its said locked position, the movement of said carrier from said locked position swinging the pivot of the lock bolt in a direction to release said lock bolt from the locking action of said disk tumblers. 90
9. A permutation lock having a lock housing which comprises a rear cup-shaped housing member of sheet metal and a flanged sheet metal front plate fitted therein, a partition plate, fixed in said housing having a sleeve extending through the front plate, a dialing means having an operating knob rotatably mounted on said sleeve outside the housing and having an extension through the front plate, disk tumblers in the housing one of which is fast on said knob extension while the others are rotatably mounted on said sleeve, the flange of said front plate abutting against said partition, and the rim of said cup-shaped rear housing member being spun over the front plate, whereby the parts are permanently secured in assembly. 100

10. A permutation lock having a lock housing, disk tumblers therein, a rotary dial plate on the front of the housing, an operating knob therefor, a click ring arranged between said dial plate and front wall of the housing, said knob having a stepped slotted extension, the dial plate, click ring, front wall of the housing and first disk tumbler being mounted on said stepped extension and keyed therewith by internal lugs of said parts engaging the slots of said extension, and the inner end of said extension being swaged to the first disk tumbler whereby the parts are secured in assembly.
11. In a shackle lock, a shackle locking mechanism including a pivoted locking dog adapted to engage the shackle when inserted, disk tumblers for locking said dog in shackle-engaging position, said dog having an index member and said tumblers having recesses adapted to be registered with said index member to release the dog, said dog when released being displaceable by withdrawal of the shackle, said index member moving into and out of said recesses as the dog moves to and from releasing position, the proportions of said recesses and index member being such that the movement of the dog to and from released position causes a rotation of said tumblers, and spring-pressed cam means engaging certain of said tumblers, the latter having cam surfaces which when the dog moves to shackle-engaging position are brought to a position such that said cam means bears thereon and shifts the tumblers having such cam surfaces to a position to cause the locking of the dog.
12. In a shackle lock, a shackle locking mechanism including a pivoted locking dog engageable with the shackle, means to cause a snap action of the dog to engage the shackle when the shackle is inserted, disk tumblers cooperable with said dog to lock the same in shackle-engaging position, the dog when released from the locking action of said tumblers being displaceable by withdrawal of the shackle, permutation controlled means for adjusting said disk tumblers to release the dog, and key-operable means for shifting the pivot of the dog while in engagement with the shackle sufficiently to move the dog clear of the disk tumblers and thereby release it from the locking action of said tumblers.
13. In a shackle lock, a shackle-locking mechanism including a pivoted locking dog engageable with the shackle, disk tumblers cooperable with said dog to lock the same in shackle-engaging position and adapted to be adjusted to release the dog for retraction, and key-operable means for shifting the pivot of the dog while in engagement with the shackle sufficiently to move the dog clear of said tumblers and thereby release it for retraction.
14. In a shackle lock, a shackle-locking mechanism comprising a swinging lock bolt operable to move into shackle-retaining position by insertion of the shackle and to be displaced from such position by withdrawal of the shackle when the mechanism is in a release condition, disk tumblers for holding said lock bolt in shackle-retaining position, permutation controlled means for adjusting said tumblers to establish a release condition of the mechanism, and key-operable means for independently establishing a release condition comprising a carrier to which the lock bolt is pivoted arranged to shift the lock bolt pivot sufficiently to free the lock bolt from cooperative relation with the disk tumblers.
15. A combined key and permutation lock comprising disk tumblers, a pivoted lock bolt, a key-operable rocker to which the lock bolt is pivoted, and key-controlled tumbler means normally holding said rocker in such position that the disk tumblers can lock the lock bolt in its locking position, said rocker adapted to be moved upon actuation of said key-controlled tumbler means to a position whereby the disk tumblers are ineffectual for the locking function.
16. In a shackle lock, a shackle locking mechanism comprising a lock bolt cooperable with the shackle, disk tumblers cooperable with said lock bolt to lock the same in shackle engaging position and adapted to be adjusted to release said lock bolt, said lock bolt when so released being displaceable from shackle-engaging position by manipulation of the shackle, said lock bolt having a part cooperating with the tumblers to cause rotative movement of the tumblers as the lock bolt moves to and from shackle-engaging position, and spring pressed cam means engaging certain of said tumblers, the latter having cam surfaces which when the lock bolt moves to shackle-engaging position are brought to a position such that said cam means bears thereon and shifts the tumblers having such cam surfaces to a position to cause the locking of the lock bolt.
17. In a shackle lock, a shackle locking mechanism comprising a lock bolt cooperable with the shackle, a disk tumbler cooperable with said lock bolt to lock the same in shackle latching position, said tumbler having a recess adapted to be adjusted to position to receive a part of said lock bolt whereby to permit a release movement of said lock bolt, said part and walls of said recess coacting in the movement of said lock bolt to and from shackle engaging position to cause a rotative movement of said tumbler, a spring pressed cam means engaging said tumbler, and a cam surface on said tumbler which on the movement thereof accompanying movement of said lock bolt to shackle-engaging position is brought to a position such that said cam means bears thereon and shifts the tumbler to position to cause locking of said latch means.
18. In a shackle lock, a shackle locking mechanism comprising a lock bolt operable to move into shackle-retaining position by insertion of the shackle and to be displaced from such position by withdrawal of the shackle when a release condition of the mechanism is established, disk tumblers for holding said lock bolt in shackle-retaining position, permutation controlled means for adjusting said tumblers to establish said release condition, a tumbler having means cooperable with a part of said member whereby to cause a rotative movement of the tumbler as said lock bolt moves to and from shackle-retaining position, a spring pressed cam means engaging said tumbler, and a cam surface on said tumbler which in the movement thereof accompanying movement of said lock bolt to shackle-retaining position is brought to such a position that said cam means bears thereon and shifts said tumbler to position to cause locking of said lock bolt.
19. A lock mechanism comprising a lock bolt adapted to be protracted and retracted, disk tumblers cooperable therewith to lock the same in protracted position, said disk tumblers having recesses adapted to be registered in a position to receive a part of said lock bolt so as to permit retractive movement thereof, permutation controlled means for adjusting said tumblers to ef-

fect such registry, said part and walls of said recesses coacting to cause a rotative movement of said tumblers accompanying the protraction and retraction of said lock bolt, and spring pressed cam means engaging certain of said tumblers, the latter having cam surfaces which when the lock bolt moves to protracted position is brought to such a position that said cam means bears thereon and shifts the tumblers having such cam surfaces to a position to cause locking of the lock bolt.

20. A lock mechanism comprising a lock bolt adapted to be protracted and retracted, disk tumblers for holding said lock bolt in protracted position, permutation controlled means for adjusting said tumblers to release the lock bolt for retraction, said lock bolt and a tumbler having coactive means whereby to cause a rotative movement of said tumbler accompanying protraction and retraction of said lock bolt, a spring pressed cam means engaging said tumbler, and a cam surface on said tumbler which in the movement thereof accompanying protraction of the lock bolt is brought to such a position that said cam means bears thereon and shifts said tumbler to a position to cause locking of said lock bolt.

21. A lock mechanism comprising a lock bolt, a disk tumbler cooperable therewith to lock the same in protracted position and adjustable to position to release the same, said tumbler having a recess to be entered by a part of said lock bolt when retracted, said part and walls of said recess coacting to cause a rotative movement of the tumbler accompanying protraction and retraction of the lock bolt, a spring pressed cam means engaging said tumbler, and a cam surface on said tumbler which in the movement thereof accompanying protraction of the lock bolt is brought to such a position that the said cam means bears thereon and shifts the tumbler to a position to cause locking of said lock bolt.

22. In a shackle lock, a shackle locking mechanism including a pivoted locking dog engageable with the shackle, disk tumblers cooperable with said dog to lock the same in shackle-engaging position, the dog when released from the locking action of said tumblers being displaceable by withdrawal of the shackle, permutation controlled means for adjusting said disk tumblers to release the dog, and key-operable means for shifting the pivot of the dog while in engagement with the shackle sufficiently to move the dog clear of the disk tumblers and thereby release it from the locking action of said tumblers.

23. In a shackle lock, a shackle locking mechanism including a pivoted locking dog engageable with the shackle, means to cause a snap action of the dog to engage the shackle when the shackle is inserted, disk tumblers cooperable with said dog to lock the same in shackle-engaging position, the dog when released from the locking action of said tumblers being displaceable by withdrawal of the shackle, permutation controlled means for adjusting said disk tumblers to release the dog, and key-operable means for shifting the pivot of the dog while in engagement with the shackle sufficiently to move the dog clear of the disk tumblers and thereby release it from the locking action of said tumblers, said means to cause a snap action comprising a spring which resists displacement of the dog from shackle-engaging position whether the dog is released from locking action of the tumblers by adjustment of said tumblers by the permuta-

tion controlled means or by operation of said key-operable means.

24. In a shackle lock, a shackle locking mechanism including a pivoted locking dog engageable with the shackle, means to cause a snap action of the dog to engage the shackle when the shackle is inserted, disk tumblers cooperable with said dog to lock the same in shackle-engaging position, the dog when released from the locking action of said tumblers being displaceable by withdrawal of the shackle, permutation controlled means for adjusting said disk tumblers to release the dog, and key-operable means for shifting the pivot of the dog while in engagement with the shackle sufficiently to move the dog clear of the disk tumblers and thereby release it from the locking action of said tumblers, said means to cause a snap action comprising a spring the relationship of which to the dog is not substantially disturbed by operation of said key-operated means.

25. In a shackle lock, a shackle locking mechanism including a pivoted locking dog engageable with the shackle, means to cause a snap action of the dog to engage the shackle when the shackle is inserted, disk tumblers cooperable with said dog to lock the same in shackle-engaging position, the dog when released from the locking action of said tumblers being displaceable by withdrawal of the shackle, permutation controlled means for adjusting said disk tumblers to release the dog, and key-operable means for shifting the pivot of the dog while in engagement with the shackle sufficiently to move the dog clear of the disk tumblers and thereby release it from the locking action of said tumblers, said key-operable means comprising a carrier having said pivoted dog and means to cause a snap action mounted thereon.

26. In a shackle lock, a shackle locking mechanism comprising a lock bolt operable to move into shackle-engaging position by insertion of the shackle and to be displaced from such position by withdrawal of the shackle when the mechanism is in a release condition, disk tumblers for holding said lock bolt in shackle-engaging position, permutation controlled means for adjusting said tumblers to establish a release condition of the mechanism, and key-controlled means for independently establishing a release condition comprising a carrier having said lock bolt movably mounted thereon, said carrier being key-operable to shift the lock bolt while in engagement with the shackle sufficiently relative to the tumblers to free the lock bolt from the locking action of the tumblers.

27. In a shackle lock, a shackle locking mechanism comprising a lock bolt operable to move into shackle-engaging position by insertion of the shackle and to be displaced from such position by withdrawal of the shackle when the mechanism is in a release condition, disk tumblers for holding said lock bolt in shackle-engaging position, permutation controlled means for adjusting said tumblers to establish a release condition of the mechanism, and key-controlled means for independently establishing a release condition comprising a pivoted carrier having said lock bolt movably mounted thereon, said carrier being key-operable to shift the lock bolt while in engagement with the shackle sufficiently relative to the tumblers to free the lock bolt from the locking action of the tumblers.

EDWIN W. NORTH.
